ADJUSTABLE MOUNTING MEANS FOR WARDROBES

Filed March 29, 1950

UNITED STATES PATENT OFFICE

2,674,767

ADJUSTABLE MOUNTING MEANS FOR
WARDROBES

John T. Fairhurst, Forest Hills, N. Y.; Emily Ellen Fairhurst, executrix of said John T. Fairhurst, deceased

Application March 29, 1950, Serial No. 152,725

1 Claim. (Cl. 20—16)

1

This invention relates to wardrobes particularly useful for public buildings, schools, offices and the like, and constitutes an improvement of my United States Patent 1,911,225 issued May 30, 1933.

The wardrobe described in my prior patent comprises one or more pairs of doors that may be moved in unison for opening and closing the wardrobes, the doors being moved from a closed position in front of the wardrobe and parallel to the rear wall thereof to an open position within the confines of the wardrobe and parallel to the side walls thereof. In the installation of groups of wardrobes of this character the doors when in the closed position are intended to provide a smooth uninterrupted wall completely enclosing the wardrobe and presenting the appearance of an ordinary wall of the building. It is important therefore that the doors be accurately aligned one with the other to provide a smooth continuous wall when in closed position.

With the use of concrete or other similar material as a flooring material in public buildings, the problem of alining doors of the wardrobes has become exceedingly difficult as the bottom supports when securely fastened in position cannot be readily moved to remedy or correct any misalignment of the bottoms of the doors.

The present invention provides a new and improved floor support for the pivotally mounted doors which support need only be approximately positioned when secured to the floor, means being provided on the support itself for accommodating any misalignment thereof and thus enabling accurate and precise alignment of the doors when in closed position.

These and other objects of the invention will become more apparent in the following description and accompanying drawings forming part of this application.

In the drawings,

Fig. 1 is a perspective view of a number of wardrobes with the doors on three of the wardrobes in the open position;

Fig. 2 is a cross-sectional view taken along the line 2—2 of Fig. 1;

Fig. 3 is a cross-sectional view of the wardrobe taken along the lines 3—3 of Fig. 2;

Fig. 4 is a cross-sectional view of a floor mount for pivotally supporting the wardrobe doors in accordance with the invention;

Fig. 5 is a cross-sectional view taken along the line 5—5 of Fig. 4; and

Fig. 6 is an exploded view of the floor mount illustrated in Fig. 4.

2

The wardrobe, of which this invention constitutes an improvement, is illustrated in Figs. 1 to 3 inclusive and is provided with a pair of doors 10 with each door being mounted for rotation about a vertical rod 12. The vertical rods 12 are mounted for rotational movement on upper and lower pivotal mounts 14 and 16, the upper mount being fastened to the top 18 of the wardrobe which may be made of wood or other similar material. The lower mount 16 is secured to the floor of the building preferably by suitable screws or bolts depending on the construction of the floor.

Each door is supported on its rod 12 by brackets 20 and 22 that are fixedly mounted to the rod 12 and are pivotally attached to the door by brackets 24 and 26.

As the doors 10 are moved from the closed position such as that shown in the wardrobe designated by the letter A in Fig. 1 to an open position such as the wardrobe designated by the letter B in Fig. 1, the doors pivot relative to the brackets 20 and 22 and the brackets in turn rotate with the rod 12 about the longitudinal axis of that rod. The fully opened and fully closed position of the doors is clearly illustrated in Fig. 3.

When the doors of these wardrobes are in the closed position they present in effect a solid wall. The wardrobes, therefore, are particularly useful, for example, in classrooms since a blackboard can be carried on the outer side of each door so that when the doors are closed sufficient blackboard space is available for the classes and at the same time adequate places for the students' clothing are also provided. It is important however that the doors be accurately alined when in the closed position. In other installations of course the doors may carry suitable panels so that when the wardrobes are closed the appearance of a normal or panelled wall is presented.

To present a uniform appearing wall it is necessary that all of the doors be accurately alined one with the other and considerable difficulty has been experienced in alining the bottom 45 of the doors 10, especially in instances where the wardrobes are installed in buildings having concrete floors. The alinement of the upper part of the door of this wardrobe is accomplished at the factory as the upper pivots 14 for the rods 12 can be accurately positioned on the upper walls 18 in the fabrication of the wardrobe. When the wardrobe is installed in a particular location, however, the bottom pivot 16 may be fastened for instance to a concrete floor requiring the drilling of holes in the concrete floor and

the insertion of lead inserts in the holes to receive the mounting screws and hold the pivot 16 firmly in place. Accurate location of the pivot 16 is difficult because it is most easily installed before the doors are erected and in the case of concrete floors cannot be easily moved. The invention herein concerns an adjustable lower pivot mounting for the rod 12 to compensate for inaccuracies in location of the pivot and to enable the accurate and precise adjustment of the lower portion of the doors 10 after the doors are in position in the wardrobe. This pivot mounting is shown in Figs. 4, 5 and 6.

This mounting comprises a flanged base part 30 having three openings 32 spaced at approximately 120° intervals for securing the mounting in place on the floor of the building in which the wardrobe is to be installed. In the upper neck-like portion 34 of the base 30 is a vertical passage 36 having an elongated or oval transverse section and terminating at the bottom in a tapered or conical mouth 38.

Transversely of the neck-like portion 34 is a slot 40 for slidably receiving a rectangular block or nut 42. The nut 42 when in position in the slot 40 threadably receives a shaft 44 which extends through the opening 36 of the base. With the shaft 44 engaging the nut 42 considerable transverse movement of the shaft relative to the base is provided for by reason of the elongated slot 36. A lock nut 46 is threaded on to the shaft 44 and is used to lock the shaft in position in the base when the proper transverse adjustment thereof has been obtained.

The bottom part of the rod 12 is illustrated in Figures 4 and 6 showing one of the transverse bracket members 22 which is fastened to the rod 12 on one end and supports the bottom of a door 10 at the other end. Within the rod 12 is a pivoted member 48 having a cone-shaped end part 50 adapted to cooperate with a conical recess 52 in the upper end of the shaft 44. The rod 12 extends downwardly beyond the conical pivot part 50 to partially overlap the shaft 44 and prevent any possibility of the pivot 50 from being forcibly urged out of the recess 52. A hole 54 is provided in the shaft 44 for the insertion of a transverse member to rotate the shaft 44 when the door is being adjusted to correct the vertical positioning of the door.

When this pivot assembly is employed as the bottom pivot 16 for the doors, as shown in Figures 1 and 2, the long axes of the transverse section of the passage 36 is placed in a position perpendicular to the rear wall 18' of the wardrobe. When the wardrobe is completely assembled and the doors 10 are in the closed position, the lock nut 46 is loosened and the shaft 44 is rotated upwardly or downwardly to adjust the

vertical position of the door. The shaft 44 is then moved toward or away from the rear wall 18' to effect the alinement of the door 10 with each of the other doors in the closed position so that all of the doors form in effect a single plane surface. Upon completion of adjustment the lock nut 46 is then tightened against the upper surface of the base 30.

In order to facilitate the adjustment of the pivot assembly and hold the block or nut 42 in place while the nut 46 is tightened, a set screw 42' is threaded through the neck of the base portion 30 and bears against one side of the block 42 to hold the block in position after the proper adjustment is made and while the lock nut 46 is tightened to permanently fix the adjustment.

With this improved base it is apparent that in the installation of wardrobes on concrete floors the bases 16 need only be approximately positioned and fastened securely to the floor, all further adjustments of the rod 12 relative to the base being accomplished by means on the base itself.

I claim:

In a wardrobe of the type having a pair of doors each supported by a vertical rod spaced from one side of the door and a pair of vertically spaced arms each fastened at one end to a rod and at the other end to a door, adjustable means for pivotally supporting each rod for rotary movement comprising a base for each rod having a vertical passage therein of elliptical transverse section for a portion of its length, said base being formed with a horizontal slot intersecting said portion of the passage, a rectangular member horizontally slidably in said slot, a shaft extending into said passage and threadably engaging the rectangular member, the upper end of said shaft having a bearing surface for support of said rod, a nut threaded on said shaft above said base, and releasable means for locking said rectangular member in any adjusted position in said slot whereby the position of the lower end of a rod may be adjusted horizontally by sliding said member horizontally in said slot.
